VIBRATIONPROOF LAMP

Gustav Hershberg, Maplewood, N. J., assignor to
Atlas Specialty Co., a corporation of New Jersey

Application August 28, 1935, Serial No. 38,146

4 Claims. (Cl. 176—39)

This invention relates to lamps and is directed to the art of electric incandescent lamps. In its more specific aspect the invention is directed to a novel type of electric incandescent lamp structure that finds particular utility in factories and the like where the electric lighting units are subjected to a large number of vibrations per minute over periods of many hours whether the lighting units be energized or de-energized.

It has heretofore been appreciated that when lamps are used in factories or other places where sewing machines, electric motors and the like are in operation that the lamps are subjected to vibration. The vibrations per minute of the lamp may sometimes be as high as three thousand. Because of these vibrations which ordinarily are neither visible nor felt, incandescent electric lamps subject to these vibrations have had a comparatively short life. In order to provide a lamp having a longer life when in such use it has been proposed to extend the leading-in conductors a considerable distance beyond the filament at the point of weld, and to weight the ends of the leading-in conductors. This construction serves to lower the amplitude of vibration at the points of engagement of the leading-in conductors and the filament. Another type of construction proposed is to employ a metallic support intermediate the glass arbor and the press so that the entire interior metallic structure shall vibrate as a unit. In the course of my observations of lamps of this type that have been subjected to vibration, I have not found them to be a real solution.

In consequence thereof I have developed a novel lamp, hereinafter described which may be manufactured at a reasonable cost and which when employed as lighting units in places where it is subjected to a large number of vibrations per minute, it has a relatively long life when compared with the life of said other lamps in similar use.

An object of my invention is to provide an electric incandescent lamp especially adapted to be employed in those places where it will be subjected to a large number of vibrations per minute.

Another object of my invention is to provide a novel vibration resistant incandescent lamp having a reasonably long life.

These and other objects of my invention will be readily apparent from the following description and appended drawing, wherein

Figure 1 represents an elevation of an incandescent lamp embodying my invention.

Figure 2 represents an elevation at right angles to that of Figure 1.

Figure 3 represents a plan view of a spacer element of my invention.

As shown in the drawing, the incandescent lamp comprises a vitreous bulb 10 integral with a vitreous reentrant stem 11. The upper portion or what I term the free end of the stem 11 is in the form of a pinch or press 12 in which are embedded a pair of spaced leading-in conductors 13. A pair of supporting and leading-in conductors 14 are sealed in the press and are connected to the conductors 13.

Integral with said press and extending therefrom is a glass arbor or rod 15 having the extreme outer part of its free end in the form of a button 16 whose diameter is about two or three times that of the arbor 15. The free end of the arbor 15 is the outer portion thereof which is remote from press 12 and includes button 16. The glass arbor 15 extends along the longitudinal center line of the bulb 10 and the conductors 14 are parallel to each other, and are bent away from the glass arbor 15 and are in a plane which does not include the arbor 15.

A coiled tungsten filament 17 of the "ring" type is located in a plane located a material distance away from the button 16 and has its ends welded to and/or clamped to the supports 14. Clamping of the ends of the filament may be accomplished by bending over a small portion of the outer ends of the supports 14 on themselves with the filament ends therebetween and pressing together under pressure the upper portions of the body of the supports, said outer ends and the filament ends therebetween. Equally spaced around about 180° of the button 16 and securely embedded therein are anchor wires 18, 19 and 20 which extend both laterally and vertically away from the button 16. These anchor or filament support wires are of much smaller diameter than the corresponding dimension of the supports 14 and their outer ends may be in the form of loops wrapped around the filament 17 to maintain the same in position. Instead of wrapping or looping these thin support wires around the filament, they may be welded thereto, as shown, or welded and also looped or wrapped. The points of connection between the filament 17 and wires 18, 19 and 20 are about 30° apart.

In accordance with my invention I have found that best results are obtained with a lamp that is to be subjected to a great deal of vibration by having the filament and supporting conductors as a unitary structure so that there shall be sub-

stantially no vibration between the filament and supports and especially at those points between these elements where they are joined together by welding. Therefore, I have provided a pair of 5 relatively thin anchor wires 21 which are embedded in the button 16. These wires are spaced about 60° apart and each wire is about 60° from the anchor wire closest thereto. These two wires 10 21 extend outwardly from the button 16 and are in a plane substantially parallel to the plane of the filament 17. The other ends of these anchors 21 are looped around and/or welded to the supports 14.

Instead of employing anchor wires 21, I may 15 employ an anchor means of the type illustrated in Figure 3. The novel anchor means may be composed of a transparent or translucent material, such as mica or the like, which may be relatively thin, rigid and inexpensive. It may be of 20 a generally V shape, with an enlarged portion 22 at the apex thereof and a pair of arms 23. An opening 25 is located at the approximate center of portions 22 and although its diameter may be greater than the corresponding dimension of 25 arbor 15, I prefer that it be equal to or less than the diameter of arbor 15, so that there shall be a snug fit between the anchor means and arbor when assembled. Because the diameter of the arbor 15 is not constant throughout its length 30 30 and because the diameter of the arbors 15 employed in production are not exactly the same I provide a plurality of radial slits 26 in the portion 22. These slits extend outwardly from the circumference of said opening 25.

When the slits are employed, I prefer that the diameter of the opening 25 shall be materially smaller than the diameter of the arbor 15. The length of the slits 26 may be such that the button 16 may be projected through the opening 25 40 even when the diameter of this opening is materially less than that of arbor 15.

An opening 27 is located at the outer portion of each arm 23 and its diameter may be greater, slightly less than or equal to the diameter of the 45 supports 14. If desired the diameter of openings 27 may be materially less than the corresponding dimension of supports 14, and a plurality of spaced radial slits 28 may extend outwardly from the circumference of said openings.

The anchor means may be assembled with 50 the supports 14 and arbor 15, by simultaneously sliding the arbor 15 and the supports 14 through the respective openings 25 and 27. When these openings have a diameter materially less than 55 the diameters of the arbor 15 and the supports 14, the slotted portions of the anchor means defining the openings 25 and 27 are flexed and bent so as to form a snug and tight fit between arbor 15, supports 14 and the anchor means.

Slits or narrow slots 28' may extend from the outer extremity of the arms 23 and into the 60 openings 25. A slot or narrow slit 29 may be located in the enlarged portion 22 and may extend from the inner apex of the anchor means 65 and into the opening 25. Although these slits or slots may be straight, I prefer that they be curvilinear as shown.

A further modification of an anchor means is 70 a thin rigid glass element having the same general exterior form as the anchor or spacer shown in Figure 3. This element may be fused directly to the arbor 15 and this element which may replace the button will have the anchor wires 18, 19 and 20 embedded in the enlarged portion 22

thereof and the supports 14 may be embedded in the outer ends of the glass arms.

When assembled the spacers or anchor means are located at the upper end of the arbor and the outer ends of arms 23 frictionally engage the 5 supports 14 at the upper portions thereof and preferably at points directly opposite the button 16, with the spacer being in a plane parallel to the filament 17.

Lamps constructed in accordance with the 10 teachings as above set forth have actually been employed in the field and have been found to be entirely satisfactory. I believe that the reason for the satisfaction rendered by lamps embodying my invention has been due to the fact that 15 the lamp is vibration resistant and therefore vibrationproof. That is, there is very little, if any, cantilever beam action between the enclosed parts of the lamp during vibration of the socket and envelope. 20

Although my invention has been described with minute particularity, it is to be limited only by the prior art.

What is claimed is:

1. A vibrationproof lamp comprising a vitreous envelope, a reentrant stem having a press, a plurality of supporting conductors embedded in said press, a vitreous arbor integral with said press and extending a material distance therefrom, a filament, a plurality of anchors carried 30 by said arbor and secured to said filament, a rigid mica spacer carried by said arbor at the free end thereof remote from said press and connected to said supporting conductors to prevent vibration of said supporting conductors. 35

2. A vibrationproof lamp comprising a vitreous envelope, a reentrant stem having a press, a pair of supporting conductors embedded in said press, a vitreous arbor integral with said press and extending upwardly therefrom, a rigid mica 40 spacer, said spacer having three openings therein, said spacer being located at the free end of said arbor, with the arbor extending through one of said openings and the supporting conductors extending through the other two of said openings 45 to reduce vibration of said supporting conductors.

3. A vibrationproof lamp comprising a vitreous envelope, a reentrant stem having a press, a plurality of supports embedded in said press, a vitreous arbor integral with said press and extending upwardly therefrom, a filament connected to said supports, a mica spacer having an opening therein, said arbor extending through said opening, the diameter of said opening being less than the diameter of said arbor, said spacer having two other openings, said supports extending through these openings, said spacer being located at the upper end of said arbor, slits extending outwardly from the circumference of one of said openings. 55

4. A vibrationproof lamp comprising a vitreous envelope, a reentrant stem having a press, a plurality of supports embedded in said press, a vitreous arbor integral with said stem, a "ring" type filament secured to said supports, a spacer having openings therein, short slits extending outwardly from the circumference of one of said openings and terminating within the perimeter of said spacer, a slit extending from the perimeter of said spacer to the circumference of one of said openings, said spacer being located close to the upper extremity of said arbor and said supports extending through said spacer. 65 70
